UNITED STATES PATENT OFFICE.

VANDEVERE TIFFIN, OF TACOMA, WASHINGTON, ASSIGNOR, BY DIRECT AND MESNE ASSIGNMENTS, TO COMBO MANUFACTURING CO., OF SEATTLE, WASHINGTON.

CONVERTIBLE FURNITURE.

1,340,467.

Specification of Letters Patent. Patented May 18, 1920.

Application filed November 3, 1917. Serial No. 200,455.

To all whom it may concern:

Be it known that I, VANDEVERE TIFFIN, a citizen of the United States, residing at Tacoma, in the county of Pierce and State of Washington, have invented a new and useful Improvement in Convertible Furniture, of which the following is a specification.

This invention relates to improvements in convertible furniture, and more particularly 10 to improvements in convertible toy furniture for the amusement of children that are playing with dolls.

The object of this invention is to provide a cheap and substantial piece of toy furniture that may be used either as a bed-crib or 15 high chair for a doll, the same being quickly and easily convertible from one to the other.

The further object is to construct a piece 20 of toy furniture of this class, that may be made of wood as well as metal, and that has comparatively few parts, and is simple in its mode of operation, so that any child can readily manipulate the same.

The device consists essentially of a chair 25 portion comprising seat, back, side arms and rear legs and an auxiliary portion adapted to be folded to form the front legs of a chair or extended to coöperate with the chair portion and form a crib.

30 The invention consists in the novel construction, adaptation and combination of parts, as will be more clearly described in the following specification, illustrated in the accompanying drawings, and finally pointed 35 out in the appended claims.

In the drawings, Figure 1 is a view in elevation of the device as it may appear when 40 it is extended to form a crib; Fig. 2 is a view in elevation of the same device as it may appear when it is folded to form a high-chair; Fig. 3 is a view in cross section on broken line 3.3 of Fig. 1; Fig. 4 is a view in elevation of a piece of furniture constructed in accordance with this invention as it may appear 45 when extended to form a crib, the same being similar to the device shown in Fig. 1, except that a tray and foot board are provided thereon for use when the device is employed as a high-chair; Fig. 5 is a plan view 50 of the device shown in Fig. 4; Fig. 6 is a view in elevation of the device shown in Fig. 4 as it may appear when folded to form a high-chair; Fig. 7 is a view in front elevation of the device shown in Fig. 6; and Fig. 55 8 is a view in cross section substantially on

broken line 8.8 of Fig. 7, certain parts being broken away.

Referring to the drawings, throughout which like reference numerals designate like parts, the numerals 1 and 2 respectively designate the legs upon which the body of the device is supported when it is used as a crib. 60 The legs 1 are spaced apart and are formed integral with or rigidly secured to side pieces 3 which form the side arms of a chair section. The side pieces 3 are rigidly connected at their rear sides by a back member 65 4 and at their bottom by a seat member 5.

Hinged to the front edge of the seat member 5, and of equal width therewith, is a 70 bed plate 6 that is adapted to extend parallel with the seat 5 and coöperate therewith to form a bottom for the crib when the device is extended, as shown in Fig. 1.

The legs 2 are secured to the member 6 75 near the outer end thereof by pivots 7, and are connected by a cross piece 8 adapted to engage beneath the plate 6 and form a stop to support the legs in substantially vertical position when the device is used as a crib. 80 The legs 2 are further connected by another rigid cross piece 9, which forms a brace and strengthens the supporting structure.

10 is an end plate that is pivotally secured, as at 11, to the plate 6, and extends upwardly in an angular position to form one end of the crib.

The plate 10 is connected with the side arms 3 by two oppositely disposed links 12, that serve as sides for the crib, the links being connected with the plate 10 by pivots 13 and with the side arms 3 by pivots 14. The pivots 14 are preferably in the form of thumb screws that may be tightened to insure the proper amount of friction between 95 the links 12 and the side arms 3.

15 are vertical supports that are connected by a pivot 16 with the links 12 and are provided near their lower ends with slots 17 that are slidable on pins 18 disposed to project sidewise from the plate 6 about mid-way between the two ends thereof.

When the device is used as a crib the pins 18 engage the bottom ends of the slots 17 and the plate 6 is supported by the links 15 105 in parallel relation with the chair seat 5.

The legs 2 are provided on the upper ends with fixedly secured lever arms 20, that extend outwardly and upwardly from the pivots 7, and are articulated by pins 21 with 110

the end of links 22 that are fixedly secured by pivots 23 to the side members 3. The links 22, when thus connected, serve to turn the legs 2 upwardly into the inoperative position shown in Fig. 2 when the device is folded to form a high-chair.

When the device is extended, as shown in Fig. 1, the outer ends of the links 12 will be supported in an elevated position by the end plate 10 and the vertical supports 15 will serve to support the plate 6 in a horizontal position in parallel relation with the chair seat 5. The device thus forms a substantial and rigid crib structure, the horizontal links 12, the vertical supports 15 and the side arms 3 forming the sides of the crib, the plate 6 and the chair bottom 5 forming the bottom of the crib and the back portion 4 and end plate 10 forming the two opposite ends of the crib.

When it is desired to fold the device to form a high-chair, the hand may be placed underneath the plate 6 and chair seat 5 below the point where they are pivotally connected with each other by the hinges 6' and an upward pressure exerted. At the same time the end opposite the chair portion may be lifted slightly off of the floor and turned downwardly into the position shown in Fig. 2.

When the device is thus folded, the links 12 approach a vertical position and serve as the front legs of the chair, the plate 6 is turned downwardly into an angular position beneath the chair, the plate 10 is turned into a substantially horizontal position beneath the chair and adjacent to the bottom end of the legs 1 and 12 and the legs 2 are turned upwardly by the action of the links 22 into an inoperative position substantially as shown in Fig. 2 where they will be out of the way.

The friction within the pivots 14 and the engagement of the bottom ends of the links 12 with the floor will maintain such legs in a substantially upright position so that the device may be used as a chair.

When the device is folded the links 15 become inoperative, the pins 18 sliding within the slot 17, see Fig. 2.

If desired, one of the links 22 may be connected with each of the legs 2, but this is unnecessary since the legs 2 are rigidly connected with each other by a cross piece 8 and 9 and one link 22 on one side of the crib will serve to operate both of these legs when the device is folded.

The back portion 4 is provided with a hand hold 24, as more clearly shown in Fig. 3, and the end plate 10 is preferably provided with a similar hand hold (not shown) to facilitate lifting the device.

The convertible chair and crib, shown in Figs. 4 to 8 inclusive, is constructed in substantially the same manner as the structure

shown in Figs. 1, 2 and 3, except that certain additional features comprising a tray and a foot board, together with suitable mechanism for operating the tray and foot board when the device is folded, are provided thereon.

Referring more specifically to Figs. 4 to 8, the numeral 25 indicates the side arms, 26 the back, 27 the seat and 28 the rear legs of the chair portion of a piece of furniture 75 constructed in accordance with this invention.

29 is a bed plate articulated by pivots 30 with the front edge of the seat portion and normally adapted to be supported in a horizontal plane parallel with the seat portion to act in conjunction therewith in forming the bottom of a crib.

Legs 31 are secured by pivots 32 to opposite sides of the plate 29 adjacent the outer 85 end thereof.

The legs 31 are rigidly connected with each other by a cross bar 33, that engages the lower side of the plate 29 to serve as a stop and limit the outward movement of 90 the legs when the device is extended to form a crib. One of the legs 31 is provided with a rigidly mounted lever arm 34 that extends upwardly and outwardly from the pivot 32 and is connected with a link 35 that is 95 secured by a pivot 36 to the side arm 25.

It is obvious that a link 35 may be connected with each of the legs 31 if desired, but this is not necessary since both of such legs are rigidly secured together by the cross 100 brace 33.

The end of the crib opposite the back 26 is formed of two plates or members 37 and 38 that are hinged to each other as indicated at 39.

The member 37 is secured by pivots 37' between rigid blocks 40 on each side of the plate 29 and the top end of the member 38 is connected on each side by pivots 41 with links 42. The links 42 extend lengthwise of 110 the crib and are connected by thumb screws 43 with the upper corners of the chair arms 25. The thumb screws 43 may be tightened occasionally to insure sufficient friction between the links 42 and the chair arms 25 115 to cause the links to stand in the upright position, as shown in Fig. 6, without slipping.

As shown in Fig. 4, the hinged portion 39 of the end plates 37 and 38 will be slightly to the rear of a line jointing the centers of 120 the pivots 37' and 41 when the device is extended. The end plates 37 and 38 thus serve as links which slightly pass center and form a lock which will prevent the crib from being folded to form a chair until the links 125 are moved inwardly past center through the position shown by dotted lines.

The bed plate 29 is supported in horizontal position by vertical supports 44 that are secured to the links 42 by pivots 45 and are 130

connected with the plate 29 by pins 46 in the plate, that work in slots 47 in the supports.

5 The back portion 26 and plate 38 are preferably provided with hand holds 26' and 38' respectively.

48 is a tray that is secured by two braces 49 to the bed plate 29, the tray 48 being adapted to lie partially within a recess 50 in 10 the back portion 26 and the members 49 being adapted to lie upon the seat portion of the chair where they will be out of the way when the device is extended to form a crib.

51 is a foot board that is cut from the 15 central portion of the plate 29 and is mounted on pivots 52 so that it may be turned either at right angles or parallel with the plate 29.

20 The foot board 51 is pivotally connected with one end of a link 53 which extends through an aperture 54 at one side of the foot board and has its other end pivotally connected with the lower portion of the chair seat 27 at a point slightly in the rear of the 25 pivots 30.

30 By this form of connection, it will be seen that when the plate 29 is turned downwardly at substantially right angles to the chair seat 27, the link 53 will automatically turn the foot board 51 outwardly into a horizontal position, as shown in Fig. 8.

35 It will also be seen that when the plate 29 is turned downwardly into a vertical position the tray 48, which is fixedly secured thereto by the members 49, will be turned upwardly into a horizontal position like the tray of an ordinary highchair, with its rear corners adjacent the front corners of the chair arms 25.

40 When the device is used as a chair, the back plates 37 and 38 will fold together, as shown in Fig. 6, thus permitting the plate 29 to assume a substantially vertical position and the tray 48 and foot board 51 to be 45 moved into their correct positions, as shown in Fig. 8.

50 While this combined chair and crib is primarily intended to be constructed and used as a toy, it will be understood that the same may be made of suitable size and strength 55 to be used as an infant's crib and chair if desired.

It is obvious that changes in the form of construction and arrangement of the various parts of this device may be resorted to within the scope of the following claims.

What I claim, and desire to protect by Letters Patent, is:

1. A device of the class described comprising a chair portion having rear legs fixedly mounted thereon, and provided with a seat, a back and side arms, a bed plate hinged to the front edge of said seat, legs pivotally mounted on said bed plate, an 60 end plate articulated with the outer end of said bed plate, links connecting said end plate with said side arms and supports connecting said bed plate with said links.

2. A device of the class described comprising a chair section having a chair back, 70 a chair seat and side arms, legs supporting the rear side of said chair section, a bed plate hinged to the front edge of said chair seat, legs pivoted to the outer end of said bed plate, an end plate, links connecting 75 the upper ends of said end plate with said chair arms, said links being adapted to form the front legs of a chair when they are folded, supports connecting said links and said bed plate for sustaining said bed plate 80 in a horizontal position and means for automatically moving said pivotally mounted legs into a position where they will be out of the way when the device is folded to form a chair. 85

3. A device of the class described comprising a chair portion having a back, a seat, and side arms, and provided with fixedly mounted rear legs, a bed plate hinged at the inner end to the front edge of said 90 seat, legs pivoted adjacent the outer end of said bed plate, stops engageable below said plate to limit the outward swinging movement of said legs, lever arms fixed to said legs and extending upwardly and forwardly 95 from the pivots thereof, links articulated at one end with the ends of said lever arms, the opposite ends of said links being secured to said chair portion, an end plate pivoted to the outer end of said bed plate and extending 100 upwardly therefrom, links pivotally secured to the upper end of said end plate and to said chair arms respectively and vertical supports articulated with said links and having slot and pin connections with 105 the sides of said bed plate.

4. A device of the class described comprising a chair section having a chair back, a chair seat and side arms, legs supporting the rear side of said chair section, a bed plate hinged to the front edge of said chair seat, a foot rest pivoted on said bed plate, means for automatically turning said foot rest into the plane of said bed plate when said bed plate is parallel with said chair 110 seat and into a plane at right angles to said bed plate when said bed plate is at right angles to said chair seat, a tray, means rigidly secured to said bed plate for supporting said tray, legs pivoted on 115 the outer end of said bed plate to support the same in a horizontal position, means for automatically folding said legs out of the way when said bed plate is moved into a vertical position, an end plate pivoted 120 to the end of said bed plate, said end plate being formed of two pivotally connected sections, links connecting said chair arms with the upper portions of opposite sides 125 of said end plate, said links being adapted 130

to form the front legs of a chair when the device is folded and supporting members articulated with said links and connected by slot and pin connections with the opposite sides of said bed plate to support the same in a horizontal position.

5. A device of the class described comprising a chair portion having side arms, a seat, and a recessed back and provided with 10 fixedly mounted rear legs, a bed plate hinged at its inner end to the front edge of said seat, a tray, supports rigidly connecting said tray to said bed plate, whereby said tray is adapted to lie within the recess in said chair 15 back when said bed plate is in a horizontal position and is supported horizontally in front of said chair arms when said bed plate is in a vertical position, legs pivoted adjacent the outer end of said bed plate, lever arms 20 fixedly secured to said legs, links articulated at one end with said lever arms and at the opposite end with a fixed support, an end plate composed of two sections pivotally connected with each other, the bottom end 25 of the lower section being pivotally secured to the outer end of said bed plate, links pivotally secured to said chair arms and to the upper end of the top section of said end

plate and vertical supports articulated with said links and having slot and pin connections with the side of said bed plate.

6. A device of the class described comprising a chair portion having rear legs fixedly mounted thereon and provided with side arms, a back, and a seat, a bed plate 35 hinged to the front edge of said seat and having a recess therein, a foot rest pivoted within said recess, a link articulated with said foot rest and with a fixed part of said chair portion to maintain said foot rest in 40 a horizontal position when said bed plate is moved into a vertical position, legs pivotally mounted on said bed plate, an end plate comprising two pivotally articulated sections, the lower end of the lowermost of 45 said sections being pivotally secured to the outer end of said bed plate, links connecting the upper sections of said end plate with said side arms and supports connecting said bed plate with said links.

Signed by me at Seattle, Washington, this 27th day of October, 1917.

VANDEVERE TIFFIN.
